UNITED STATES PATENT OFFICE

WILLIAM J. TAYLOR, OF WINTHROP HARBOR, ILLINOIS, ASSIGNOR TO THE LAMSON COMPANY, OF SYRACUSE, NEW YORK, A CORPORATION OF MASSACHUSETTS

CONVEYER

Application filed September 19, 1927. Serial No. 220,445.

This invention relates to certain new and useful improvements in conveyers.

Where it is desirable to deflect or shunt boxes or containers from a main conveyer on to a branch track, siding or other conveyer, particularly in connection with gravity conveyers, the rolls of the gravity conveyer which are arranged with their axes at right angles to the direction of movement of containers passing along the main track tend to resist the necessary turning of the containers to direct them into the branch track or siding due to the fact that the containers must turn and move at an angle to the direction of rotary movement of the rolls in order to get into the branch. The main object of this invention is the production of a conveyer of such construction that the rolls or rollers are free to turn so that their axes 10 may be disposed at various angles to the direction of movement of containers passing along the main conveyer, such turning movement of the rolls being actuated by the moving containers themselves and as a result 15 conforming substantially to the direction of movement of the containers passing into the branch track whereby any substantial resistance to the deflection of the container from the main conveyer is practically eliminated.

A further object resides in the provision 20 of means for normally maintaining the rolls or rollers with their axes perpendicular to the direction of movement of containers along the main conveyer and for returning the rolls or rollers to such position after any shifting movement so that normally they will not 25 frictionally resist the free movement of containers along the main conveyer.

Other objects and advantages relates to the details of the structure and the parts thereof, all as will more fully appear from the following description, taken in connection with the accompanying drawings in which:—

Figure 1 is a sectional view of a conveyer of this invention taken on line 1—1, Figure 4.

Figure 2 is a sectional view taken on line 2—2, Figure 4.

Figure 3 is a sectional view taken on line 3—3, Figure 4.

Figure 4 is a sectional view taken on line 4—4, Figure 1.

Figure 5 is a sectional view through one of the rollers and its supporting mechanism.

Figure 6 is a top plan view of one of the 55 rollers and its supporting mechanism.

The apparatus of this invention is adapted for many and various associations and for the purpose of illustration is here shown as a section of a main conveying apparatus. 60

As shown the gravity conveyer indicated generally at —1— is interposed between two belt conveyers —2— and —3— respectively which may be of any usual and ordinary construction and it will be apparent that the 65 interposition of the gravity conveyer of this invention between two belt conveyers is merely for the purpose of illustrating one practical use of the invention.

The gravity conveyer —1— may consist of 70 any suitable frame-work —4— including a floor or bottom wall —5— and an overhead frame —6— carrying a plurality of deflecting bars —7— forming guide-ways for a purpose to be hereinafter described. 75

Upon the bottom wall —5— there are mounted a plurality of rolls or rollers —8— upon which a container such as the illustrated at —9— is adapted to move forwardly due to the fact that the contact surface defined by the rolls inclines downwardly from the conveyer —2— to the conveyer —3— and this inclination may be easily effected by supporting the bottom wall or floor —5— in such inclined position. 80

Ordinarily the conveyer rolls have been supported upon stationary axes disposed at right angles to the direction of movement of containers —9— along the conveyer and as before suggested such disposition of the rolls 90 frictionally resists their movement into a branch or siding —10— disposed at one side of the main conveyer and, for the purpose of eliminating this resistance and permitting free and easy movement of the containers 95 into a branch conveyer or siding, a number of comparatively narrow rolls —8— are utilized at least for the contact surfaces at the end of the gravity conveyer over which the containers must first move in passing into the 100

branch —10— and these rolls are separately mounted for free movement in shifting their axes at various angles to the direction of movement of containers along the main track 5 so that the rolls may conform their direction of rotation to substantially the direction of movement of a container passing into the branch —10—, such shifting of their axes of rotation to various angles with respect to 10 the direction of movement of a container along the main conveyer being effected by the movement of the container itself in turning and moving into the branch —10—.

It will be apparent that these rolls may 15 be mounted in various and many manners and by various structure to permit free shifting movement of their axes as actuated by a moving container and for the purpose of illustration there is shown a mounting for such rolls 20 which is satisfactory for the purpose.

Such construction is best illustrated in Figures 5 and 6.

Each roll —8— may be mounted by a ball-bearing —11— upon a shaft —12— secured 25 in the opposite arms —13— and —14— of a yoke —15—, the bottom wall of which may be secured in any suitable manner as by rivets to a disk —16— constituting one member of a ball-retainer, the other member of which 30 may be in the form of an annular convex ring —17— having a substantially flat flange —19— secured to a plate —20— connected to the base or bottom wall —5— in any suitable manner as by bolts —22—.

35 Balls —23— are disposed between the one member —16— and the other member —17— of the bearing.

The disk —16— is separated from the plate —20— by a suitable ball bearing —24— 40 so that the disk —16— may freely rotate between the balls —25— and the balls —23— but is restrained from other movement.

In order to maintain the rolls —8— with 45 their shafts —11— normally disposed at right angles to the direction of movement of containers along the main track while permitting comparatively free and easy angular shifting movement of said axes a spring —26— has one end connected to a post —27— 50 rising from and connected to the bottom wall —5—, the other end of the spring being connected in any suitable manner to the yoke —15—, this position of the parts being such that after any angular shifting movement of 55 the axis of a roll —8— its respective spring —26— returns it to a normal position with its axis perpendicular to the direction of movement of containers along the main track.

For the purpose of deflecting containers 60 into a predetermined selected branch track, such containers, as best illustrated in Figures 1 and 2, are formed at the upper portion of their front and rear ends with a series of laterally disposed holes or sockets —29— for 65 the reception of a guide pin —30—.

These sockets conform in number with the guideways between the deflecting bars —7— and by placing pins —30— in desired sockets so that they will pass between selected deflecting plates the container when it reaches the gravity conveyer —1— will be guided by the deflecting plates and the pins so as to pass into a predetermined branch track and as illustrated the guideways for each branch track as formed by the deflecting bars —7— 70 extend in proper disposition above each branch track —10— so as to guide the container properly into the branch track, the container itself shifting the rolls —8— so that their direction of rotation is substantially the same as the direction of movement of the container.

The rolls —31— in the branch track may be mounted upon fixed axes properly inclined and disposed to permit free movement of the 80 containers into the branch track without substantial frictional resistance.

85 This invention is not concerned with any further disposition of the containers after 90 they have been deflected into a branch track but in Figure 4 there is illustrated a belt conveyer —32— adapted to receive containers deflected into the branch track —10—.

At the discharge end of the gravity conveyer —1— and beyond the point where the containers in moving into the branch track —10— will contact with the rolls it is possible to make the rolls of the same width as the conveyer and to mount them upon fixed axes 95 as illustrated at —33—.

100 It is, however, desirable as shown to have all of the rolls over which the container moves along the main track and into a branch track so mounted that their axes of rotation may be shifted by a container to substantially conform with the direction of movement of the container and although there is shown a specific structure together with a particular form, association and relation of the parts thereof, I do not desire to restrict myself to any particular association of a gravity conveyer or to the details of the structure shown or the form and relation of the parts thereto as various changes and modifications may be made without departing 105 from the spirit of the invention as set forth in the appended claims.

110 I claim:

115 1. A conveyer comprising a main conveyer portion and a branch portion leading therefrom, means for deflecting articles transported by the main conveyer portion to the branch portion, said main conveyer portion including a plurality of rotatable rolls the plane 120 of rotation whereof is controlled by the passage of articles thereover and variable thereby to conform to the direction of movement of an article passing from the main conveyer portion into the branch portion, and means for automatically returning the rolls to a 125 130

- position with their axes substantially perpendicular to the direction of movement of an article passing along the main conveyer portion after each shifting movement.
- 5 2. A conveyer comprising a main conveyer portion and a branch portion leading therefrom, means for deflecting articles transported by the main conveyer portion to the branch portion, said main conveyer portion including a plurality of rotatable rolls capable of automatically varying their direction of rotation independently of each other to conform to the direction of movement of an article passing from the main conveyer portion into the branch portion, and means for automatically returning the rolls to a position with their axes substantially perpendicular to the direction of movement of an article passing along the main conveyer portion 10 after each shifting movement.
- 10 3. A conveyer comprising a main conveyer portion and a branch portion leading therefrom, said main conveyer portion including a roll, a yoke in which the roll is journaled, and means for rotatably supporting the yoke, and a spring connected to the yoke and tending normally to maintain the yoke in predetermined position.
- 15 4. A conveyer comprising a power driven conveyer, a second power driven conveyer, a gravity roller conveyer connecting said power driven conveyers, a plurality of rotatable rolls capable of shifting their axes of rotation in said gravity roller conveyer, and a branch gravity roller conveyer in communication with the gravity roller conveyer.
- 20 5. A conveyer comprising a main conveyer portion and a branch portion leading therefrom, said main conveyer portion including a plurality of rotatable rolls capable of automatically varying their plane of rotation to conform to the direction of movement of an article passing from the main conveyer portion into the branch portion, a plurality 25 of fixed deflectors above the main track, and means on an article being conveyed for engaging a selected deflector whereby the article being conveyed will be deflected from the main conveyer portion into a selected branch conveyer portion.
- 30 6. A conveyer comprising a main conveyer portion and a branch portion leading therefrom, said main conveyer portion including a plurality of rotatable rolls capable of automatically varying their plane of rotation to conform to the direction of movement of an article passing from the main conveyer portion into the branch portion, means for automatically returning the rolls to a position with their axes substantially perpendicular to the direction of movement of an article passing along the main conveyer portion after each shifting movement, a plurality 35 of fixed deflectors above the main track, and means on an article being conveyed for
- engaging a selected deflector whereby the article being conveyed will be deflected from the main conveyer portion into a selected branch conveyer portion.
- 40 7. A conveyer comprising a main conveyer portion and a branch portion leading therefrom, means for deflecting certain articles transported by the main portion to the branch portion, said main conveyer portion including a plurality of rotatable rolls having their axes normally substantially perpendicular to the direction of movement of an article passing along the main conveyer portion and being free to vary their plane of rotation by engagement of a deflected article to conform 45 to the direction of movement of such article from the main conveyer portion into the branch portion, and means for automatically returning the rolls to the normal position after each shifting movement.
- 45 8. A conveyer comprising a main conveyer portion and a branch portion leading therefrom, means for deflecting certain articles transported by the main portion to the branch portion, said main conveyer portion including a plurality of rotatable rolls having their axes normally substantially perpendicular to the direction of movement of an article passing along the main conveyer portion and being free to vary their plane of rotation independently of each other by engagement of a deflected article to conform to the direction of movement of such article from the main conveyer portion into the branch portion, and means for automatically returning the rolls 50 to the normal position after each shifting movement.
- 50 In witness whereof I have hereunto set my hand this eighth day of September, 1927.
